CLAIM

The ornamental design for a floor fan tower, as shown and described.

DESCRIPTION

FIG. 1 is a left front side perspective view of a floor fan tower.

FIG. 2 is right front side perspective view of the floor fan tower of FIG. 1.

FIG. 3 is a left rear perspective view of the floor fan tower of FIG. 1.

FIG. 4 is a right rear perspective view of the floor fan tower of FIG. 1.

FIG. 5 is a left side view of the floor fan tower of FIG. 1.

FIG. 6 is a right side view of the floor fan tower of FIG. 1.

FIG. 7 is a front view of the floor fan tower of FIG. 1.

FIG. 8 is a rear view of the floor fan tower of FIG. 1.

FIG. 9 is an enlarged top view of the novel floor fan tower design of FIG. 1.

FIG. 10 is a greatly enlarged cross-sectional view of the floor fan tower taken along lines 10—10 of FIG. 7.

FIG. 11 a left front side perspective view of a second embodiment of the floor fan tower.

FIG. 12 is a right front side perspective view of FIG. 11.

FIG. 13 is a front side view of FIG. 11.

FIG. 14 is a left side view of FIG. 11.

FIG. 15 is a right side view of FIG. 11; and,

FIG. 16 is a greatly enlarged cross-sectional view of the floor fan tower taken along lines 16—16 of FIG. 13.

The broken line showing of the top, sides, stand, buttons, and rear grill of the floor fan tower is included for the purpose of illustrating environmental structure and forms no part of the claimed design.
